UNITED STATES PATENT OFFICE.

HENRY L. DOYLE, OF NEW YORK, N. Y.

DESIGN FOR A CALENDAR.

SPECIFICATION forming part of Design No. 33,675, dated December 11, 1900.

Application filed October 17, 1900. Serial No. 33,384. Term of patent 3½ years

To all whom it may concern:

Be it known that I, HENRY L. DOYLE, a citizen of the United States, and a resident of the borough of Manhattan, city, county, and State of New York, have invented and produced a new and original Design for Calendars, of which the following is a specification, reference being had to the accompanying drawings, forming part thereof.

10 Figure 1 is a front elevation of a calendar showing my new design. Fig. 2 is an edge view of same.

15 The leading feature of my design consists of a rectangular calendar secured to a backing on which is arranged certain ornamentalations, as shown in said drawings.

20 1 represents a cardboard or backing on which is secured in any appropriate manner a rectangular calendar 2.

25 3, 4, 5, 6, 7, 8, 9, and 10 designate ornamentalations secured to said cardboard or backing 1, said ornamentalations having the appearance of a staff of music at the top, and extend-

ing across said cardboard a coin, a cigarette, a cigar, a match, poker-chips, a poker-hand 25 of cards, and a mug or glass, arranged as shown in the drawings.

11 represents a shoestring.

My complete design as viewed in front elevation has the appearance of a cardboard or 30 backing on which is secured a rectangular calendar, and all of the several parts so shaped and arranged as to represent a bachelor's outfit.

Having thus described my design, what I 35 claim as new is—

The design for a calendar, as herein shown and described.

In testimony that I claim the invention set forth above I have hereunto set my hand this 40 13th day of October, 1900.

HENRY L. DOYLE.
